RIVETING MACHINE

Wilbur Johndrew, Buffalo, N. Y.

Original application July 28, 1942, Serial No. 452,606. Divided and this application May 11, 1944, Serial No. 535,026

5 Claims. (Cl. 78—46)

1

My invention relates in general to hydraulic riveting machines, such as shown and described in my co-pending application Serial No. 452,606, filed July 28, 1942, and more particularly to supporting and guiding means for the movable ram of such machines.

This application is a division of my co-pending application Serial No. 452,606, filed July 28, 1942.

As is well known to those skilled in the art, hydraulically operated riveting machines produce the riveting action by squeezing the exposed end of the rivet and consequently great pressure must be exerted to accomplish the work. In order to adequately bear the great pressures employed in machines of this kind, it is necessary that ample bearing surface be provided for the riveting anvil. Where the anvil is movable along supporting guideways, to adjust it to various riveting positions the co-acting bearing surfaces between the anvil and the guideway, due to their area and the pressure upon them, create considerable friction, and, therefore, considerable power is required to move the anvil during such adjustment.

It has been the principal object of my invention to provide anti-friction bearings for resiliently supporting the ram in any but its riveting position, so that it may be easily adjusted, such supporting means being of such a nature as to yield and allow the bearing surfaces to engage each other during the riveting operation.

Another object has been to provide anti-friction means for guiding the travel of the ram over its guideways during adjustment thereof.

Moreover, means are provided to hold the anti-friction guiding means in engagement with the guideways of the machine, thus compensating for any inaccuracies in parallelism due to non-alignment of the guideways.

Fig. 1 is a fragmentary side elevation, partly in section, of a riveting machine to which my invention is applicable.

Fig. 2 shows an enlarged sectional elevation of the riveting ram equipped with my invention.

Fig. 3 is a fragmentary side elevation showing one of the anti-friction units.

Fig. 4 is an enlarged fragmentary view showing the riveting ram in its normal inactive position, in which position the ram is supported above the ways with an intervening space.

Fig. 5 is a fragmentary front elevation of a modified form of my invention.

Fig. 6 is a side elevation of one of the anti-friction units of the form of invention shown in Fig. 5.

Fig. 7 is a similar view of another form of anti-friction unit employed on the same type of machine.

Fig. 8 is a plan view of the portion of the invention shown in Fig. 7; and,

Fig. 9 is a sectional elevation of that form of

2

unit shown in Figs. 7 and 8, taken on line IX—IX of Fig. 8.

As clearly shown in Fig. 1, my invention is applicable to a machine having a bucking unit 12 and a riveting unit 13 mounted within the framework 14 of the machine for transverse movement across the central opening 15 thereof. The bucking ram and riveting units are movable across said opening preferably in unison. Means are provided for moving the riveting unit which may be of any suitable or desired form. For convenience of illustration I have shown an electric motor 16 attached to a reducing unit 20 of any suitable form and connected to a feed screw 21 by means of a drive shaft 22 and suitable gearing 23. The gearing is connected to a feed screw nut 24 which is held by any suitable means in non-axial relation with the end wall 25 of the housing. The inner end of the feed screw is suitably attached to the riveting anvil so that the anvil may be moved back and forth within the opening 15. For convenience of illustration I have omitted the drive mechanism for the bucking ram 12, but obviously this may be driven in unison with the riveting ram by the same type of means and by the same motor as that shown and described in connection with the feeding of the riveting unit.

Referring now to Fig. 2, the riveting unit comprises a cylinder 26 having a reciprocating ram 27 slidably mounted therein and carrying a riveting anvil 30 at its upper end. The cylinder 26 is attached to the head 31 of the hydraulic cylinder 33. This cylinder is provided with a piston 32 having an upwardly extending plunger 34 which is mounted for movement in the upper end of the head 31. The upper end of the plunger is attached to the lower end of the ram 27 by means of a stud 35.

The hydraulic cylinder 33 is provided with ports 36 and 37 for conducting fluid under pressure to the cylinder to cause the piston therein to be moved in either direction to actuate the ram.

The head 31 is provided with an overhanging flange 38 at each side which is provided with a lower bearing surface 40. This bearing surface extends over and is supported by a bearing surface 41 formed on the upper face of each of the guideways 42. When the ram is being forced upwardly to effect a riveting operation, the surfaces 40 and 41 are in contact with each other and the guideways 42 take the thrust of the riveting operation. When, however, the riveting pressure upon the ram has been released, it is desirable to counter-balance the weight of the riveting unit and such counter-balancing action may be brought to a point when the surfaces 40 and 41 will be slightly separated, thereby providing a space 43 therebetween, as clearly shown in Fig. 4 of the drawings. In order to accomplish this

counter-balancing or supporting action, I provide an anti-friction mounting unit 44 at each side of the head 31. Each of these units comprises anti-friction rollers 45, each of which is rotatably carried by a yoke 46. Each yoke is mounted upon a pivot pin 47 and is pressed downwardly toward the surface 41 by means of a spring 50. A supporting bracket 51, secured to the side of the head, is provided for each of the units and the yokes 46 are mounted thereon for vertical adjustment in any suitable manner. I prefer, however, to mount each of the yokes upon a pivot pin 47, carried by the bracket 51, as shown in Fig. 3. Each of the brackets 51 has outwardly extending flanges 53 near its upper edge, each of which engages one end of each of the springs 50, the other end of each spring bearing against the outer face of the co-acting yoke. Each of the springs may be mounted upon a pilot 54 which is carried by each of the flanges 53.

The springs 50 are so designed that their combined resistance against compression is sufficient to substantially counter-balance and support the weight of the riveting unit. The amount of movement of the yokes 46 about their pivot pins 47 and, therefore, the positions of the rollers 45 may be adjusted by means of set screws 52 carried by the brackets 51 and engageable with the ends of the yokes opposite the rollers.

In order to guide the riveting ram in its lateral movement across the guideways 42, I provide anti-friction guide rollers 55 which are carried by the head 31 and bear one against each of the inner vertical surfaces 56 of the guideways 42.

Referring now to the form of invention shown in Figs. 5 to 9, inclusive, the riveting ram 59 having a riveting anvil 60 is slidably mounted within the ram cylinder 61 which is attached to the head 62 of the hydraulic cylinder 63. The cylinder is provided with a piston and plunger (not shown) similar to that shown and described in connection with the form of invention shown in Fig. 2, and suitable ports 64 and 65 are provided for conducting fluid under pressure to the cylinder. The guideways of this form of invention are represented at 70 and 71. The head 62, as in the other form of invention, is provided with overhanging flanges 72 and 73 which are supported, respectively, by the guideways 70 and 71 by means of bearing slippers 74.

In this form of invention the mounting units carry both the anti-friction rollers 75 as well as the guide rollers 76. These guide rollers are engageable preferably with the outer guide surfaces 80 of the guideways 70 and 71. The anti-friction unit 81, shown at the left hand side of Fig. 5, is provided with a bracket 82 having a vertical leg 83 which is secured to the head 62, and with a horizontal leg 84, extending outwardly from the lower edge of the vertical leg. A recess 85 is provided at each side of the horizontal leg near the point of its attachment to the vertical leg and the anti-friction roller 75 at each side of the unit is disposed within this recess. Each of these rollers is carried by a yoke 86 formed on an arm 90. Each of the arms is pivoted at 91 to the vertical leg 83 of the bracket 82, thus permitting oscillating movement of the arm and yoke. The anti-friction rollers 75 are pressed downwardly by means of helical springs 92, one arranged above the outer end of each of the arms, having its lower end bearing against the arm and its upper end mounted within a spring washer 93 which is carried by an adjustable stud 94, screw threaded into a flange 95. This flange

is secured to the vertical leg 83 of the bracket near its upper edge.

The guide rollers 76 of this unit are each rotatably mounted upon a stud 96 which is suitably secured to the horizontal leg 84 of the bracket. As hereinbefore pointed out, these rollers are designed to engage with the outer guide surface 80 of the guideway 70.

The mounting unit 100 at the opposite side of the head 62 comprises a bracket 101 having a vertical leg 102 and a horizontal leg 103. The anti-friction rollers 75 of this unit are mounted in a manner similar to those of the unit 81 and comprise a yoke 86 carried by an arm 90, which arm is pivoted at 91 to the vertical leg 102 of the bracket. A helical spring 92 having its upper end mounted within a spring washer 93 serves to press the spring downwardly in contact with the arm 90. This spring washer 93 is carried by a spring stud 94 which is screw threaded to a flange 104 secured to the vertical leg 102 of the bracket. By means of the studs 94, the springs 92 may each be individually adjusted so as to produce the proper counter-balancing action upon the riveting unit when the ram is in its inoperative position.

The mounting unit 100 is formed with a reciprocating roller plate 105 which is slidably mounted upon the upper surface of the horizontal leg 103 of the bracket. A guide roller stud 106 is carried at each end of the roller plate and each stud carries one of the guide rollers 76 of this unit. The roller plate 105 is secured to the top of the horizontal leg 103 in slidable manner by means of bolts 110 which are passed through the horizontal leg of the bracket and have their upper ends disposed in elongated slots 111 formed in the roller plate so as to permit some movement of the plate toward and away from the vertical leg of the bracket. In order to maintain the plate in its inward position, a plate spring 112 is provided. This spring is mounted within a recess 113 formed in the central portion of the plate and the spring has one of its ends bearing against a washer 114. The other end of the spring bears against a plate abutment 115 which is secured to the roller plate, preferably flush with the inner edge thereof and having a depending portion 116 extending down into the recess 113. A stud 120 extends through the washer 115, the spring 112, and the abutment 115, and is screw threaded into the vertical leg 104 of the bracket. A nut 121 is provided on the outer end of the stud whereby the tension of the spring 112 may be regulated. For convenience of illustration the mounting units 81 and 100 are shown in Figs. 6 to 9, inclusive, as being detached from the head 62. When attached, however, as shown in Fig. 5, the rollers 76 carried by each of the units will be drawn into firm but resilient contact with the vertical bearing surfaces 80 of the guideways 70 and 71, movement of the roller plate 105 against the tension of the spring 112 serving to maintain the bearing contact and to compensate for any irregularities in parallelism of the two opposing bearing surfaces 80 of the guideways.

From the foregoing it will be clear that when riveting pressure upon the riveting ram is relieved or when it is in its normal inactive position, the anti-friction rollers 45 and 75 will, under the compressive action of the springs 50 and 92, respectively, substantially counter-balance the weight of the riveting unit and, if desired, provide a definite space 43 (see Fig. 4). This space in Fig. 4 is exaggerated for clearness of illustration.

tion, and as will be obvious, all that is necessary is that frictional contact between the bearing surfaces be relieved when adjustments are being made. While it is preferable to actually separate the bearing surfaces for even one or two thousandths of an inch, it is obvious that the springs may be so adjusted as to relieve substantially all or a large part of weight of the riveting unit, while at the same time leaving the surfaces in bearing contact. Obviously, just as soon as the ram is moved upwardly into riveting position, the sustaining action of the mounting units will be counter-acted and the surfaces between the hydraulic cylinder heads and guideways will take the entire thrust of the riveting operation.

Having thus described my invention, what I claim is:

1. A riveting machine, comprising guideways, a riveting unit having a riveting anvil and a support therefor, a mounting unit carried at each side of said riveting unit for substantially counter-balancing the weight of said riveting unit as the same is moved from one to another of a series of riveting stations, each of said units comprising a bracket carried by said riveting unit, pivotally mounted arms carried by each of said brackets, a yoke provided on each of said arms, an anti-friction roller carried by each yoke and engageable with said guideways, springs carried by said brackets and each engageable with one of said arms, and a guide roller carried by each of said brackets and engageable with vertical surfaces formed on said guideways, and means for moving the anvil on the support for riveting operation.

2. A riveting machine, comprising guideways, a riveting unit having a riveting anvil and a support therefor, a mounting unit carried at each side of said riveting unit for substantially counter-balancing the weight of said riveting unit as the same is moved from one to another of a series of riveting stations, each of said units comprising a bracket carried by said riveting unit and formed with a vertical leg and a horizontal leg, anti-friction rollers carried by each vertical leg, spring means for pressing each of said rollers into contact with a horizontally arranged surface of the associated guideway, said spring means being yieldable during riveting operation to provide direct supporting engagement of the riveting unit upon said guideways, and a guide roller carried by the horizontal leg of each bracket and engageable with vertically arranged surfaces of said guideways, and means for moving the anvil on the support for riveting operation.

3. A riveting machine, comprising guideways, a riveting unit having a riveting anvil and a support therefor, a mounting unit carried at each side of said riveting unit for substantially counter-balancing the weight of said riveting unit as the same is moved from one to another of a series of riveting stations, each of said units comprising a bracket carried by said riveting unit and formed with a vertical leg and a horizontal leg, anti-friction rollers carried by each vertical leg, spring means for pressing each of said rollers into contact with a horizontally arranged surface of the associated guideway, said spring means being yieldable during riveting operation to provide direct supporting engagement of the riveting unit upon said guideways, guide rollers carried by the horizontal leg of one of said brackets and engageable with the vertically arranged surface of one of said guideways, a roller plate slidably

mounted upon the horizontal leg of the other of said brackets, guide rollers carried by said plate for engagement with the vertical bearing surface of the other guideway, resilient means for urging said plate inwardly to bring the rollers carried thereby in yieldable contact with said bearing surface of the guideway, and means for moving the anvil on the support for riveting operation.

10 4. In a riveting machine, the combination with the riveting anvil, the anvil support, and the guideways thereof, of an anti-friction unit carried by said support and engaging said guideways, resilient means connecting said anti-friction means with said support for sustaining the weight of said anvil and said support during adjustment thereof, said means being yieldable during riveting operation to provide direct supporting engagement of the support with said guideways, oppositely arranged aligning means carried by said support and engageable with said guideways for maintaining said support in alignment therewith, resilient means for mounting one of said aligning means, whereby said support will be maintained in alignment with the guideways during adjustment, and means for moving said anvil on said support for riveting operation.

30 5. In a riveting machine, the combination with the riveting anvil, the anvil support, and the guideways thereof, of an anti-friction unit carried by said support and engaging said guideways, resilient means connecting said anti-friction means with said support for sustaining the weight of said anvil and said support during the adjustment thereof, said means being yieldable during riveting operation to provide direct supporting engagement of the support with said guideways, oppositely arranged aligning means carried by said support, each aligning means 35 comprising fixed guide rollers carried at one side of said support and engageable with the co-acting guideway, a slidably mounted plate arranged at the opposite side of said support, guide rollers carried by said plate and engageable with the opposite co-acting guideway, resilient means engaging said plate for pressing said last mentioned rollers into engagement with the co-acting guideway, and means for moving said anvil on said support for riveting operation.
